RELAY ASSEMBLING AND ADJUSTING
FIXTURE

Alexander M. MacPheat, Indianapolis, Ind., assignor to Western Electric Company, Incorporated, New York, N. Y., a corporation of New York

Application July 7, 1950, Serial No. 172,502

6 Claims. (Cl. 29—203)

1

This invention relates to assembling and adjusting fixtures and more particularly to a fixture for assembling and adjusting parts of relays.

The subject constituting the subject matter of the present invention is particularly applicable to the assembling and adjusting of parts of relays for use in telephone coin collector mechanisms which may include a pivotal armature actuated lever, pivotal spring returned restoring levers for said armature actuated lever and an associated armature carried upon a saddle member pivoted intermediate its ends on a frame which is fixed relative to a pair of coils having their cores fixed to a base plate, the lever, restoring levers and saddle member being pivoted about a common axis on the frame by front and rear pivot screws. In this type of relay, it is very essential that sloping end faces provided on the armature be associated with sloping side faces on the cores with definite and similar air gaps therebetween and that the pivotal saddle member to which the armature is fixed should have a slight play between its pivot screws within prescribed limits to insure that the relay will have the desired operating characteristics.

An object of this invention is the provision of a fixture for accurately and expeditiously assembling and adjusting parts of relays.

In accordance with the above object, the invention comprises a fixture which includes pivotal wedged-faced locating means movable into cooperative relationship with the sloping side faces of the coil cores for longitudinally shifting and centering the relay sub-assemblage comprising the base plate with the coils and their cores and frame fixed thereto to a definite position on the fixture, means for locking the locating means in its operated position, and clamping means for holding the thus positioned relay sub-assemblage during subsequent assembling operations. After the sub-assemblage is clamped to the fixture, the wedge-faced locating means is returned to its inoperative position. Thereafter, the relay parts to be assembled on the sub-assemblage; namely, the saddle member with the armature thereon, armature actuated lever and restoring levers, are assembled and pivoted on the frame by their pivot screws, which are screw-threaded into the frame. This is followed by tightening the pivot screws to eliminate any play of the saddle member and armature on the screws and to hold the armature assemblage in a substantially horizontal plane. At this time, the armature is fixed to the saddle member by a pair of screws passing through slots in the saddle member and threaded

2

into the armature. These screws are then loosened so that the armature may later be longitudinally adjusted slightly relative to the saddle member. A lever is now actuated and, through a pin and slot connection, moves a cam yoke having cam surfaces which cooperate with cam surfaces on armature centralizing fingers to advance the latter in unison to engage the sloping end faces of the armature relative to the sloping side faces of the cores with definite and equal air gaps therebetween. While the latter lever is in its operated position, means is provided for locking the same thereat so that it cannot shift and disturb the adjustment of the armature relative to the saddle member and the sloping core side faces. The screws, previously loosened, which fix the armature to its saddle member, may then be tightened and the lever is unlocked and moved back to its normal position. It is also essential that the armature and its saddle member have a slight play on their pivot screws. To adjust the pivot screws for such play, a pivotally mounted dial indicator is first swung into operative position to carry its actuator into contact with one end of a vertical edge face of the armature and is clamped in such position. The rear pivot screw, previously tightened, is now loosened and adjusted so that the armature and its saddle member will have a slight play on its pivots within prescribed limits, which is indicated on the dial indicator by rocking the armature in a horizontal plane. The front pivot screw is now locked by means of a lock nut carried thereon and the assemblage of the referred-to relay parts on the relay sub-assemblage is complete.

Other objects and advantages of the invention will be apparent from the following detailed description taken in conjunction with the accompanying drawings, in which

Fig. 1 is a fragmentary plan view of a fixture embodying the features of this invention, the operating parts of the fixture being shown in their normal or retracted position;

Fig. 2 is a plan view, similar to that of Fig. 1, partly in section; and showing certain operating parts in operated positions with a relay sub-assemblage definitely located and clamped on the fixture;

Fig. 3 is a fragmentary vertical irregular section on a slightly enlarged scale, taken on the line 3—3 of Fig. 2;

Fig. 4 is a vertical sectional view of a portion of Fig. 3 showing the armature centralizing fingers in their operated positions with the armature end faces located relative to the relay core

side faces to provide definite and similar air gaps therebetween;

Fig. 5 is a vertical sectional view taken on the line 5—5 of Fig. 2, on a slightly enlarged scale similar to that of Figs. 3 and 4, and

Fig. 6 is a plan view of a relay after the assembling and adjusting operations have been completed on the fixture.

Referring now to the drawings, particularly to Figs. 3 and 6, there is shown a relay, indicated in general at 10, comprising a base plate 11 of magnetic material having its opposite ends notched at 12—12, the notches being used in mounting the relay on the coin collector mechanism with which it is used. The base plate 11 supports a pair of coils 17—17 having magnetic material cores which terminate in pole pieces 21—21 having sloping side faces 23—23 at their upper ends upon opposed inner faces, which in cooperation with sloping end faces 24—24 (Figs. 4 and 6) of a pivotal armature 25 leave but a small air-gap between such sloping faces when the pivotal armature is operated to take a position adjacent either of the pole piece faces. The armature structure comprises the armature proper 25 attached by screws 26—26 to a channel shaped supporting member 27. Slots 28—28, extending longitudinally in the member 27 through which the screws 26—26 extend, provide means whereby the armature 25 may be longitudinally adjusted slightly relative to the member 27. The member 27 carrying the armature 25 is pivoted intermediate its ends by front and rear pivot screws 30 and 31, respectively, on a frame 32 of non-magnetic materials, which is frictionally supported on the pole pieces 21—21 and also secured by screws 33 thereto, the frame surrounding a central magnet 35 fixed to the base plate 11. Also pivoted on the pins 30 and 31 is an armature actuated lever 36 having an offset lower slotted end 31, which in use is connected to a movable end of an associated coin directing vane (not shown) of the coin controlled apparatus which includes the relay 10.

The lever 36 includes a top portion 38 which extends over the armature assembly in spaced relation, and is slotted at 39 to provide access to the screws 26—26. Upon the front side of the lever 36 (Fig. 6) is an apertured depending lug 42, its aperture being aligned with an aperture in the downwardly extending portion of the lever 36 at the rear of the relay, the two apertures receiving the front and rear pivot screws 30 and 31, respectively, upon which the lever is pivoted, the screw 30 being equipped with a lock nut 43. Also pivoted on the screws 30 and 31 are two independent armature restoring levers 45—45 extending toward opposite ends of the armature, and each has a central depending arm 46 which normally is spring pulled against the upper end face of the adjacent pole piece 21 by coiled tension springs (not shown).

The fixture to be presently described serves to first accurately longitudinally center and then clamp the relay sub-assemblage on the fixture and after relay parts to be assembled on the sub-assemblage are assembled and pivotally mounted thereon to shift the armature 25 longitudinally on its channel-shaped supporting member 27 to accurately associate its sloping end faces 24—24 with the sloping side faces 23—23 of the pole pieces 21—21 to provide the desired air gaps therebetween and also to facilitate the providing of the armature assemblage with the desired slight play between its pivot screws 30 and 31. 75

The fixture comprises a base 51 having two irregularly shaped aligned and spaced left and right hand standards 52 and 53, respectively, (Figs. 1 and 3) fixed to its upper surface. Mounted for reciprocation in slideways 54—54 provided in the upper surfaces of the standards 52 and 53 in longitudinal alignment with the relay armature 25 are left and right hand armature adjusting fingers 55 and 56. The fingers 55 and 56 are forked shaped on their inner opposed ends (Figs. 1, 3 and 4) with the end faces of the furcations inclined as indicated at 59—59 to substantially the slope of the armature end faces 24—24 with which the fingers engage in the operation of centralizing the armature with respect to the sloping side faces 23—23 of the pole pieces 21—21. Forked ends are provided on the fingers 55 and 56 for the purpose of permitting the inclined faces 59—59 to engage the faces 24—24 of the armature 25 at either side of armature restoring lever arms 46—46. Formed transversely in the upper surfaces of the fingers 55 and 56 are similar but reversely directed cam slots 60, in which are fitted lower ends (Figs. 1 and 2) of correspondingly shaped reversely directed cam arms 61 of an H-shaped reciprocatory cam member 62 having an interconnecting cross arm 63 adjacent its upper end. For supporting and guiding the member 62 in its reciprocatory movements two irregularly shaped aligned and spaced left and right hand standards 66 and 67, respectively, are carried on the base 51 at its upper end (Figs. 1 and 2) which are provided in their upper surfaces with suitably shaped and arranged guideways 68 for receiving opposite parallel arm portions of the member 62. The cam arms 61 terminate in parallel portions which are supported and guided in guideways 69 formed in the upper surfaces of the standards 52 and 53. 40 Cover plates 72 and 73 fixed to the upper surfaces of the standards 52, 53, 66 and 67 serve to retain the reciprocatory armature centralizing fingers 55 and 56 and the H-shaped reciprocatory cam member 62 which actuates the fingers in their guideways. Advance and retractive movements of the member 62 serve to simultaneously advance the fingers 55 and 56 equal distances toward each other and then retract them, respectively, the movements of the fingers being perpendicular to the movements of the member 62.

For actuating the H-shaped member 62, a hand lever 74 is pivoted at its left end (Figs. 1 and 2) as indicated at 75 to a lug 76 welded to the left hand vertical surface of the standard 66 (Figs. 1 and 3), the lever being pivoted by a pin and slot connection 79 to the crossarm 63 of the H-shaped member 62 at a point intermediate its parallel arms. To the right end of the lever 74 is attached by means of a pin 81, a handle 82, the pin being fixed at one end to the handle and its opposite end is screwthreaded at 83 and freely threadable into an aperture 86 in the lever 74. Attached to the right hand vertical surface of the standard 67 is an arcuately shaped vertical support 87 for the end of the lever carrying the handle 82. An unthreaded portion 88 of the pin 81 rides in a slot 89 in the support 87, which support is tapered in thickness from its upper end to its lower end as viewed in Figs. 1 and 2. In operation upon the lever 74 being moved from its normal full line position to its advanced dotted outline position Fig. 2, during which operation the H-shaped cam member 62 is advanced, which in turn simultaneously advances the armature centralizing fingers 55 and 56 equal distances to

ward each other, the handle 82 is rotated to thread the pin 81 further into the lever 74, thus clamping the left end face of the handle against the arcuate and tapered support 87 at its thin end. Thus, there will be no tendency for the lever 74 to unloosen and creep back to its retracted position, but rather it will tend to creep in the direction of its advance movement, thereby insuring that the fingers 55 and 56 will remain in their advanced operative positions, as shown in the drawings.

Spanning and intermediate the standards 66 and 67 and secured to lower surfaces thereof, is a plate 90 having upon its upper surface adjacent its lower end Figs. 1 and 2 two pair of apertured spaced lugs or ears 93-93 and 94-94. Pivoted to the lugs 93-93, as indicated at 95-95, is an irregularly shaped yoke member 96 having lower ends of its furcations, Figs. 1 and 2, directed inwardly in alignment with each other and then downwardly (Figs. 3 and 5) and shaped to provide two depending lugs 97-97. The lugs 97-97 are recessed as indicated at 98-98 to clear the screws 33. Outer opposed faces 99-99 of the lugs 97-97 are inclined to substantially the slope of the side faces 23-23 of the armature pole pieces 21-21 and are similarly spaced. When the yoke member 96 is swung from its inoperative position, Figs. 1 and 5 to its operative position, Figs. 2 and 5, the inclined or wedge faces 99-99 will wedgingly engage the sloping faces 23-23 of the core pieces 21-21. Pivoted at 100 upon and between the arms of the yoke member 96 is a cam lever 101 which is forked at 102 (Fig. 5). Supported in and extending between the apertured lugs 94-94 on the plate 90 is a fixed pin 103 which is engaged by an inclined surface 104 on the forked end 102 of the cam lever 101 when the lever is swung from its inoperative position, Fig. 1, to its operative position, Fig. 5. This produces a cooperating camming action of the pin 103 and surface 104 which serves to draw down the yoke member 96 to force its wedge faces 99-99 along the sloping faces 23-23 of the relay pole pieces 21-21, and thus shifting the relay sub-assemblage longitudinally in one direction or the other to centrally locate it upon the assembling fixture. The cam lever 101 will remain in its operated position until released.

For clamping the sub-assemblage of the relay 10 to the fixture, the fixture base 51 carries a pair of aligned and spaced plates 107-107 from the upper surfaces of which extend relay locating pins 108-108 which are adapted to enter the notches 12-12 in the relay base plate 11. Slidably mounted on the plates 107-107 for longitudinal movement are clamp plates 109-109 (Fig. 3), which are adapted at inner ends to be engaged with the upper surfaces of the notched ends of the relay base plate 11. It is to be understood that the relay locating pins 108-108 do not extend quite up to the upper surface of the relay base plate 11. Each of the clamp plates 109-109 is slotted, as indicated at 110, at its inner end and is forked at its outer end as indicated at 111. A headed pin 112 extends through the slot 110 and is threaded into the base 51. A compression spring 115 surrounding the pin 112 and bearing at opposite ends against the under surface of the clamp plate 109 and the upper surface of the plate 107, normally urges the clamp plate upwardly above the plane of the upper surface of the relay base plate 11. Pivoted at 116 to each clamp plate 109 at its forked outer end is a lever 117 having a cam formation 118, which bears

against the upper surface of the plate 107 when the right hand lever is rocked counterclockwise, Fig. 3, thus lowering the inner end thereof into clamping relation with the relay base plate 11. The slot 110 in the clamp plate 108 permits the clamp plate to slide over the relay base plate 11 and to be retracted therefrom preceding the clamping of the relay 10 on the fixture by the cam levers 117-117 and following the movement of the cam lever to its inoperative position. In their outermost longitudinal positions, the clamp plates 109-109 do not interfere with the mounting of the relay 10 on the fixture.

Attached to the under surface of the plate 90 and extending from its left end Fig. 5, is an L-shaped bracket 119 and projecting from its left-hand surface is a pin 120. The bracket 119 and the projecting pin 120 are so arranged that when the armature actuated lever 36 is assembled on the relay sub-assemblage, to be described hereinafter, the pin 120 will be received in the offset lower slotted end 37 of the lever 36, dotted outline Fig. 2, which serves to position and hold the relay lever 36 in substantially its normal position during its assembly with the other referred to relay parts, as previously mentioned, on the relay sub-assemblage.

Pivots mounted on the fixture at its left side on a vertical axis, as shown at 121 (Figs. 1, 2 and 5), is an arm 122 to one end of which is clamped at 123 a dial indicator 126. The arrangement is such that an actuator 127 of the dial indicator will engage a vertical edge face of the armature 25 at its left end, dotted outline Fig. 2, when the arm 122 is swung about its pivot 121 to its operative position (Fig. 2) and locked in such position by rotating a hand screw 128 to clamp split arms 129 of the arm 122 to its pivot member 121. One of the split arms 129 is arranged to engage an adjustably mounted stop member 130 when the dial indicator 126 is swung to its operative position as shown in the drawings.

In using the described fixtures and assuming that the pivotal yoke shaped member 96 having the spaced wedge faces 99-99 and the pivotal cam lever 101 carried thereby are in their retracted or inoperative positions, as shown in broken outline in Fig. 5, and that the hand lever 74 has been retracted to its full line position (Figs. 1 and 2), and consequently, the armature adjusting fingers 55 and 56 are in their inoperative positions. Also that the clamp plates 109-109 are in their outer released positions on the plates 107-107, and also that the dial indicator 126 has been swung clockwise about its pivot member 121 to its inoperative position (Fig. 1), the fixture is operated in the following manner.

With the various operating parts of the fixture positioned as above described, a sub-assemblage of a relay 10, which is to have the parts previously referred to accurately assembled thereon and certain of the parts adjusted, is placed upon the fixture with the notched relay base plate 11 (Fig. 3) associated with the locating pins 108-108 projecting from the fixture plates 107-107. As thus positioned the relay sub-assemblage is transversely located on the fixture by the cooperating fixture pins 108-108 entered in the notches 12-12 of the relay base plate 11.

Thereafter the pivotal yoke-shaped member 96 is rocked counterclockwise (Fig. 5) to engage the wedge faces 99-99 with the sloping side faces 23-23 of the armature pole pieces 21-21 (Fig. 3), whereupon, the pivotal cam lever 101 is like-

wise rocked counterclockwise to engage its inclined surface 104 with the fixed pin 103 which serves to draw down the wedge faces 99-99 along the sloping faces 23-23 of the relay pole pieces 21-21, which serves to accurately longitudinally center the relay sub-assemblage upon the assembling fixture. After thus longitudinally locating the relay sub-assemblage, the relay clamp plates 109-109 are slid toward each other to position their inner opposed ends over the notched ends of the relay base plate 11. This is effected by grasping and using the hand levers 111-111 to slide the plates 109-109 into position, and thereafter rocking the levers (Fig. 3) in the manner previously described to cause the plate 109-109 to firmly clamp the relay sub-assemblage to the fixture as shown in the drawings. Following the clamping of the relay sub-assemblage in position, the cam lever 101 is released, and together with the yoke-shaped member 96 20 rocked back to their inoperative positions (Figs. 1 and 5).

The relay parts, namely, the armature 25 attached to its supporting channel shaped member 27 by the screws 26-26, armature actuated lever 36 and armature restoring levers 45-45 are now assembled and pivotally mounted on the frame 32 of the relay sub-assemblage by means of the front and rear pivot screws 30 and 31, and the latter screws tightened to eliminate any play of the armature assemblage on the pivot screws, and to maintain the armature assemblage in a substantially horizontal plane. In mounting the relay lever 36 in position, the fixture pin 120 is entered in the offset lower slotted end of the lever for the purpose previously referred to. The screws 26-26, which pass through the slots 28-28 in the channel member 27, are now loosened so that the armature 25 may now be slightly longitudinally adjusted on the member 27, and thus position its sloping end faces 24-24 relative to the sloping side faces 23-23 of the relay pole pieces 21-21 to provide equal and definite air gaps therebetween. To thus position the armature assemblage, the hand lever 14 is rocked from its full line position to its broken outline position (Fig. 2), and locked in such position as previously described. This movement of the lever 14 serves to advance the armature adjusting fingers 55 and 56 equal distances, and thus longitudinally positioning the armature 25 on its longitudinally fixed supporting member 27, as previously described to provide the desired air gaps between the ends of the armature and the relay pole pieces. Following this actuation of the lever 14, the screws 26-26 are tightened to hold the armature 25 to the member 27 in its adjusted position.

Following this adjustment of the armature 25, the lever 14 is unlocked and rocked back to its inoperative full line position (Figs. 1 and 2), and the dial indicator 126 is now swung about its pivot 121 to carry its actuator 127 into engagement with the vertical edge face of the armature 25 at its left end as indicated fragmentarily in broken outline in Figs. 2 and 6 and clamped in such position. Thereafter, the rear pivot screw 31, previously tightened, together with the front pivot screw 30 is adjusted outwardly while transversely wobbling the armature assemblage until it has a slight play within prescribed limits, as indicated on the dial indicator 126, between its pivot screws. This is followed by locking the front pivot screw 30 in position by means of the lock nut 43, and the assembling and adjusting

operations on the relay in the present fixture are completed.

To remove the thus assembled and adjusted relay 10 from the fixture, the operations described hereinbefore in mounting the relay sub-assemblage on the fixture, are simply reversed.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A relay assembling and adjusting fixture for use in positioning a relay armature on a support relative to faces of spaced coil cores and holding said armature in that position while it is fixed to said support which is pivotally mounted intermediate said core faces comprising a base member, means on said base for supporting slidably a relay having spaced coil cores, a plate pivotally mounted on said base member and carrying two sloping faces, the surfaces of said faces being disposed in planes corresponding to the planes which the core faces will occupy when centrally positioned in the fixture, a pin fixed to said base, a cam lever carried by the pivotal plate for engagement with said pin to force the sloping faces on said pivotal plate into tight engagement with the core faces upon manipulation of the cam lever when the plate is in a position substantially parallel with the ends of the cores thereby to locate the relay assemblage in the fixture preparatory to the assembling therewith of other parts of the relay, and means for clamping the relay assemblage to said base member to hold the relay assemblage in its located position after movement of said plate to an unoperative position.

2. A relay assembling and adjusting fixture for use in positioning a relay armature on a support relative to sloping faces of spaced coil cores of a relay and holding said armature in that position while it is fixed to said support which is pivotally mounted intermediate said core faces comprising a base member, means on said base member for supporting such a relay slidably relative to the base, a plate pivotally mounted on said base member and carrying two cam faces, the surfaces of said faces being disposed in planes corresponding to the planes which the core faces will occupy when centrally positioned in the fixture, a pin fixed to said base, a cam lever carried by the pivotal plate for engagement with said pin to force the cam faces on said pivotal plate into tight engagement with the core faces upon manipulation of the cam lever when the plate is in a position substantially parallel with the ends of the cores thereby to locate the relay assemblage in the fixture preparatory to the assembling therewith of other parts of the relay, means for clamping the relay against movement relative to the base when it has been so located, a cam slide slidably mounted on said base, means for actuating said cam slide, a pair of oppositely disposed and oppositely shaped cooperating cams carried by the cam slide, and a pair of diametrically opposed camming members adapted to be actuated by said cams for centralizing an armature with respect to the fixture and thus centralizing the armature with respect to said core faces of the relay which has been centralized on the fixture.

3. A relay assembling and adjusting fixture for

use in positioning a relay armature on a support relative to faces of spaced coil cores of a relay assemblage and holding said armature in that position while it is fixed to said support which is pivotally mounted intermediate said core faces comprising a base member, means on said base member for movably supporting the relay assemblage, a plate pivotally mounted on said base member and carrying two cam faces, the surfaces of said faces being disposed in planes corresponding to the planes which the core faces will occupy when centrally positioned in the fixture, a pin fixed to said base, a cam lever carried by the pivotal plate for engagement with said pin to force the cam faces on said pivotal plate into tight engagement with the core faces upon manipulation of the cam lever when the plate is in a position substantially parallel with the ends of the cores thereby to locate the relay assemblage in the fixture preparatory to the assembling therewith of other parts of the relay, means for clamping the relay assemblage to the supporting means after it has been so located, a cam slide slidably mounted on said base, a pivotal lever for actuating said cam slide, means operated by the cam slide for centralizing said armature with respect to the fixture and thus with said core faces, means for locking said cam slide actuating lever in its actuated position comprising a handle threaded into said lever, and a tapered arcuately shaped member upon one surface of which said lever rides and having a second surface against which said handle may be locked by threading the handle in one direction into said lever.

4. A relay assembling and adjusting fixture for positioning a relay armature on a support relative to opposed faces of two spaced coil cores associated with the armature to provide similar air gaps between opposite faces of the armature and the core faces comprising means for supporting the cores movably, wedging means movable relative to the supporting means to engage said core faces and move the cores, movable means mounted on said wedging means cooperating with a fixed element for forcing the wedging means to a position effective to shift said cores on said supporting means to centralize the cores with respect to said wedging means, means for clamping the cores in said centralized position on said supporting means, a pair of opposed fingers slidably relative to the supporting means adapted to engage said opposite armature faces and shift said armature upon its support to provide said air gaps in cooperation with said core faces after the cores have been centralized and said wedging means withdrawn, said fingers having camming surfaces, a pair of camming means movable relative to the supporting means in

unison at an angle to the movement of said fingers and engaging said finger camming surfaces for actuating said fingers, and means for actuating said camming means.

- 5 5. A relay assembling and adjusting fixture for positioning a relay armature on a support relative to opposed faces of two spaced coil cores associated with the armature to provide similar air gaps between opposite faces of the armature and the core faces comprising means for supporting a relay assemblage including the cores, wedging means movable relative to the supporting means to simultaneously engage said core faces, means for forcing the wedging means to a position effective to shift said relay cores on said supporting means to centralize the cores with respect to said wedging means, means for clamping the cores in said centralized position on said supporting means, a pair of slidably mounted fingers centralized relative to said wedging means adapted to engage said opposite armature faces and shift said armature upon its support to provide said air gaps in cooperation with said core faces after the cores have been centralized and said wedging means withdrawn, said fingers having camming surfaces, and means for actuating said fingers.
- 10 6. A relay assembling and adjusting fixture for positioning a relay armature on a support relative to opposed faces of two spaced coil cores associated with the armature to provide similar air gaps between opposite faces of the armature and the core faces comprising means for supporting the cores, wedging means mounted pivotally relative to the supporting means for engaging said core faces to centralize the cores with respect to said wedging means, means for clamping the cores in said centralized position on said supporting means, a pair of slidably mounted fingers adapted to engage said opposite armature faces and shift said armature upon its support to provide said air gaps in cooperation with said core faces after the cores have been centralized and said wedging means withdrawn, said fingers having camming surfaces, and a yoke shaped slidable member having camming surfaces on spaced arms thereof mounted for moving said fingers toward one another.
